CLAIM

The ornamental design for a stub shaft, as shown and described.

DESCRIPTION

FIG. 1 is a left side elevational view of a first embodiment of a stub shaft showing my new design, the right side elevational view, top plan view, and bottom plan view being identical;

FIG. 2 is a rear end elevational view thereof;

FIG. 3 is a front end elevational view thereof;

FIG. 4 is a first perspective view thereof;

FIG. 5 is a second perspective view thereof, shown in environmental use;

FIG. 6 is a left side elevational view of a second embodiment of a stub shaft showing my new design, the right side elevational view, top plan view, and bottom plan view being identical;

FIG. 7 is a rear end elevational view thereof;

FIG. 8 is a front end elevational view thereof;

FIG. 9 is a first perspective view thereof;

FIG. 10 is a second perspective view thereof, shown in environmental use;

FIG. 11 is a left side elevational view of a third embodiment of a stub shaft showing my new design, the right side elevational view, top plan view, and bottom plan view being identical;

FIG. 12 is a rear end elevational view thereof;

FIG. 13 is a front end elevational view thereof;

FIG. 14 is a first perspective view thereof;

FIG. 15 is a second perspective view thereof, shown in environmental use;

FIG. 16 is a left side elevational view of a fourth embodiment of a stub shaft showing my new design, the right side elevational view, top plan view, and bottom plan view being identical;

FIG. 17 is a rear end elevational view thereof;

FIG. 18 is a front end elevational view thereof;

FIG. 19 is a first perspective view thereof; and,

FIG. 20 is a second perspective view thereof, shown in environmental use.

The broken lines shown represent environmental subject matter and form no part of the claimed design.
